UNITED STATES PATENT OFFICE.

ALBERT ADELSON, OF SAN FRANCISCO, CALIFORNIA.

CLOSURE.

Application filed February 3, 1926. Serial No. 85,782.

This invention relates to improvements in closures.

The principal object of this invention is to provide a closure means for bottles, jars, tumblers, and like articles, which comprises a cap placed upon the bottle or the like thereby eliminating the customary turning action employed when threaded caps are utilized.

Another object is to produce a cap of this character which may be adapted to any type of bottle commonly used upon the market.

An additional object of this invention is to provide a cap which will tightly engage the flange upon the bottle or jar thereby holding the seaming element within the cap in intimate contact with the top of the bottle.

A still further object is to produce a device of this character which is cheap in construction and, therefore, well within the customary market price of closures of this nature.

Other objects and advantages will be apparent during the course of the following description.

In the accompanying drawings forming a part of this specification, and in which like numerals are employed to designate like parts throughout the same,

Figure I is a fragmentary side elevation of the top of a jar constructed in accordance with my invention,

Figure II is a vertical cross section of a bottle showing one of my caps applied thereto,

Figure III is a vertical cross section of a cap as shown in Figure IV and adapted to be employed with the jar shown in Figure I,

Figure IV is a side elevation of the jar constructed in accordance with my invention,

Figure V is a top plan view of the neck of a bottle or jar, with the depressions shown in dotted lines, and

Figure VI is a fragmentary side elevation of a jar with the closure thereon.

In the capping of bottles and jars, it is now customary to employ a closure having an indentation in the side thereof, which indentation follows a screw thread formed upon the bottle or jar, the result being that, in order to apply the closure a rotary or screwing action must take place. It is well seen that this is objectionable in factories where large quantities of bottled goods are being put up for the market, with the result that I have devised a cap which may be pressed downwardly on the top of the bottle or jar in such a

manner that it will spring over a flange formed upon the bottle or jar and tightly engage the same.

I further provide means to prevent rotation of this cap, except when desired, and further provide means whereby the cap may be bodily removed without mutilation.

In the accompanying drawings wherein for the purpose of illustration is shown a preferred embodiment of my invention, the numeral 5 designates a jar having a neck portion 6 terminating at 7. This neck portion is provided with a flange as shown at 8.

By referring to Figure V, it will be noted that this flange 8 is provided with a series of notches 9 and upon the under surface of the flange are provided depressions 11. These depressions serve to prevent accidental rotation of the cap, as will be later seen.

The construction of the bottle shown in Figure II and designated by the numeral 12 is identical with that described in Figure I, with the exception that a seat is formed at 13 against which my device is adapted to contact.

Essentially my device comprises a closure 14 having a depressed central portion 16 and a depending annular flange 17, which flange is slit as at 18 so as to permit the same to be flexed when being pressed over the flange of the bottle or jar.

At 19 I have shown a plurality of lugs formed upon the flange 17 and so shaped as to form a cam surface 21 adapted to contact the bottle flange so as to spread the annular flange during the capping process.

At 22 I have shown a seal which may be made of cork, rubber or any similar sealing material. In the form shown in Figure II, it will be noted that the depressed portion 16 is provided with inclined side walls and the cap is further depressed in depending rounded formation as at 23 so as to form a stopper extending into the neck of the bottle 12.

In employing my device, it is only necessary to place the same over the top of the bottle or jar and to force the same downwardly thereon. This downward pressure causes the cam surfaces 21 to engage the flange 8 thus spreading the closure and after passing over the flange 8 these lugs 19 engage the under surface of the flange and retain the cap in intimate contact with the top of the bottle or jar.

When it is desired to remove the closure from the bottle or jar, a partial revolution

of the same will bring the lugs 19 into line with the notches 9 after which the cap may be raised and removed.

It will thus be seen that I have produced 5 a simple device and one which will perform all of the objects above set forth.

It is to be understood that the form of my invention herewith shown and described is to be taken as a preferred example of the same, 10 and that various changes in the shape, size and arrangement of parts may be resorted to without departing from the spirit of the invention or the scope of the subjoined claim.

While I have shown my invention applied 15 to a bottle and jar, it will be obvious that it can also be used to advantage on any kind of container where a closure is necessary, or on anything where my invention can be adapted for securing one part to another.

Having thus described my invention, I 20 claim:—

In a closure, the combination with a container, a flange formed on the upper extremity thereof and being provided with a plurality of notches and depressions formed on the 25 underside of said flange, a cap for said container, a plurality of substantially triangle shape lugs formed with said cap and having their inclined surfaces arranged to provide cams engageable with the flange to spread the 30 cap over said flange, a sealing element in said cap and adapted for engagement with said container, and said lugs being adapted for engagement with the underside of said flange for arrangement in the depressions for securing 35 said cap to the container.

In testimony whereof I affix my signature.

ALBERT ADELSON.
